CLAIM

The ornamental design for a hand pump with folding nozzle, as shown and described.

DESCRIPTION

FIG. 1 is a front perspective view of the hand pump with folding nozzle, showing my new design, with the nozzle in the open position;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof.

FIG. 9 is a front perspective view of the hand pump with folding nozzle, showing my new design, with the nozzle in the closed position;

FIG. 10 is a rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken lines are for environmental purposes only and form no part of the claimed design.
